Primary Examiner — Angela J Lee*Assistant Examiner* — Shawn T Gingrich*(74) Attorney, Agent, or Firm* — Kenja IP Law PC**(57) CLAIM**

The ornamental design for an electric connector, as shown and described.

DESCRIPTION

FIG. 1 is a front perspective view of an electric connector showing our new design;

FIG. 2 is a rear perspective view thereof;

FIG. 3 is a front view thereof;

FIG. 4 is a top view thereof;

FIG. 5 is a right side view thereof;

FIG. 6 is a left side view thereof;

FIG. 7 is a rear view thereof;

FIG. 8 is a bottom view thereof;

FIG. 9 is a section view taken along line 9-9 in FIG. 4; and,

FIG. 10 is a bottom view thereof in a folded state in an environment of use.

The wires shown in broken lines in FIG. 10 represent environment and form no part of the claimed design.

1 Claim, 10 Drawing Sheets(56)
